UNITED STATES PATENT OFFICE.

EDWARD J. SOVATKIN, OF BROOKLYN, NEW YORK, ASSIGNOR TO J. SKLAR MANUFACTURING CO., OF BROOKLYN, NEW YORK, A CORPORATION OF NEW YORK.

SURGICAL PUMPING UNIT.

Application filed August 16, 1924. Serial No. 732,428.

This invention relates to surgical equipment for ear, nose and throat treatment and operations, and more particularly to an electrical equipped surgical apparatus having an 5 air pump portion demountably arranged thereon for use as a complete independent unit.

Another object of the invention is the provision of an apparatus of the character described having a table and an electrically driven air pump unit supported thereon and controlled therefrom, said unit being compactly constructed and demountable from said table to serve as a complete independent 15 unit, the table and said unit having co-operating elements whereby positioning of the unit on the table disposes the unit in co-operative relation to the apparatus.

Other objects of this invention will in part 20 be obvious and in part hereinafter pointed out.

With the above exception, the invention accordingly consists in the features of construction, combinations of elements and arrangement of parts which will be exemplified in the construction hereinafter described and of which the scope of application will be indicated in the following claims.

In the accompanying drawing, in which is 30 shown one of the various possible illustrative embodiments of this invention,

Fig. 1 is a perspective view of a surgical equipment embodying the invention;

Fig. 2 is a perspective view showing the 35 air pump as a complete independent unit dismounted from the table;

Fig. 3 is a diagram of the electric wiring circuit of the air pump;

Fig. 4 is a diagram of the electric wiring 40 circuit of the table;

Fig. 5 is a mid-section through the motor control rheostat showing the construction of the air preheater;

Fig. 6 is a cross sectional view through the 45 air pump and table connectors taken on line 6-6 of Fig. 1.

Referring in detail to the drawing, the surgical apparatus shown in Fig. 1 includes a table 10 constructed preferably of metal. 50 Said table may have shaped angle iron legs 11 mounted on rubber tired casters 12, a top 13, drawers 14 beneath the top for storing instruments and sundries, and a shelf 15.

A box 16 of rectangular cross section may 55 be secured to the table 10 with its upper

side 16^a adjacent the top 13. The side 16^a supports a motor control switch 17, gages 18 and control valves 19, the purposes of which will hereinafter be referred to, and various operating accessories not shown. 60

An air pump 20 having the parts thereof compactly mounted on a baseboard 21 is supported on the shelf 15 of the table 10. Said air pump 20 is adapted to be easily and quickly dismounted from the table 10 as a 65 unit by means of a suitable handle 22 to permit convenient transportation thereof. As seen from Fig. 2, the air pump has a motor 23 which is controlled by a rotary switch 24, and a resistance coil or rheostat 25, the latter 70 being utilized for preheating the air. Motor 23 drives a friction disc 26 which operates a pressure air pump 27 through connecting rod 28, air being delivered at outlet 29 of a purifier 30. The motor driven pumping apparatus above described may be similar to that disclosed in Patent No. 1,469,603 granted to Leopold Steiner October 2, 1923. 75

A preferred form of preheater construction is shown in Fig. 5 and comprises a hollow cylindrical resistance coil 25 which surrounds a tube 36 through which the air is passed. The inlet side 36^a of the tube 36 is normally connected by a flexible tubing 37 to the outlet 29 of the purifier 30, and the 85 outlet side 36^b of said tube 36 may be connected to supply heated air wherever needed, as for example to an ether bottle (not shown).

A suction pump 31 may also be driven from the said disc 26, the air being first passed 90 through purifier 32. The pumps 27 and 31 and purifiers 30 and 32 are practically identical with the exception that pump 27 is connected to deliver air under pressure, and pump 31 to simultaneously produce a suction at inlet 33 of the purifier 32. 95

When air pump 20 is mounted on the shelf 15, it is preferably connected to a piping system, not shown, which is incorporated in the frame work of the table 10, said system terminating with the male coupling member 34^a for the air pressure side and member 35 for the suction side on front legs 11 of the table 10 as shown in Fig. 1. 100

A dominant feature of this invention resides in the construction whereby the air pump 20 may be used and electrically controlled as a complete independent unit dismounted from the table 10 as shown in Fig. 2 or in combination with the table 10 as 110

shown in Fig. 1 as will hereinafter more fully appear.

When air pump 20 is being used as an independent unit, power to run the motor 23 is supplied through a plug connection 38 mounted on baseboard 21 and controlled by turning knob 24^a of switch 24, the motor 23 being preferably of the universal type which permits adjustment thereof for operation on direct or alternating current as is well understood. A circuit wiring diagram is shown in Fig. 3 from which it is seen that switch 24 has seven points, and setting the switch 24 on the first point, marked "Off", opens the power circuit. The second point, marked "Start" connects the motor 24 directly across the power line which is feasible and desirable in this case since the motor is small and the apparatus may thus be quickly and simply brought into operation, in the shortest possible time. The third point, marked "Low" connects in circuit the entire resistance 25 and the fourth, fifth, and sixth points successively cut out portions of the resistance in the well known manner. The seventh and last point, marked "High" cuts out the last portion of the resistance, and the motor then operates directly across the power line as it does on the second switch point.

From the description given above, it is clear that the air pump 20, as an independent complete unit may be conveniently transported and put in operation in various places to suit different requirements, as for instance, it may be removed from the table 10 in the surgeon's office and carried to a patient's home and put in service there or may be made conveniently available for other like purposes.

The air pump 20 when used in combination with a table 10 is mounted on shelf 15. This arrangement which is compact and neat permits easy interconnection of the air pump 20 with the piping system and control incorporated in the table structure, not fully shown but described in my aforementioned co-pending application for various surgical treatments and operations. As shown in Fig. 1, the control of the combined apparatus is most conveniently arranged on side 16^a of box 16 where the switch 17 having knob 17^a is handily located for controlling motor 23, the power for operation being supplied through a plug connection 40 mounted on the back side of box 16 instead of through the plug connector 38 on the air pump 20. A circuit diagram of the table wiring is shown in Fig. 4 from which it is seen that switch 17 has seven points and is similar in every respect to switch 24 described above.

The switch 17 and the connector 40 have conductor wires leading down therefrom through a conduit 41 passing under the shelf 15 and terminating in a series of spaced rigidly secured male plug members a', b', c',

d', e', and f' upstanding and extending through the shelf 15 as shown in Fig. 1. A corresponding set of female socket members a, b, c, d, e, and f are fixedly fastened to extend inwardly from the bottom side of the air pump 20 for co-operatingly engaging with the said male members, the female members being connected into the air pump wiring circuit as shown in Fig. 3.

This male and female connecting means forms a simple, easy and quick detachable mounting which interconnects the table control switch 17 on mounting the air pump 20 in place on shelf 15.

There may also be provided a pair of spaced upstanding pins 15^a secured on the shelf 15 and a corresponding spaced pair of holes 21^a extending up from the bottom of the air pump 20 to facilitate guiding the latter in proper mounting position for aligning the said male and female connector members.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A surgical apparatus comprising a table, a motor driven air pump detachably supported by the table, and an electric wiring installation having portions thereof permanently mounted on the table and on the air pump, and means for disconnecting said portions simultaneously with the removal of the air pump from said table.

2. A surgical apparatus comprising a table, a motor driven air pump detachably supported by the table, and an electric wiring installation having portions thereof permanently mounted on the table and on the air pump, and means for disconnecting said portions simultaneously with the removal of the air pump from said table, said means comprising a male connector member supported by the table and corresponding engageable female members secured to the air pump.

3. A surgical apparatus comprising a table, a motor driven air pump detachably supported by the table, and an electric wiring installation having portions thereof permanently mounted on the table and on the air pump, and means for disconnecting said portions simultaneously with the removal of the air pump from said table, said means comprising a male connector member supported by the table and corresponding en-

gageable female members secured to the air pump and means for guiding said connector members to aligning position when mounting said air pump on the table.

5. 4. A surgical apparatus comprising a table having a shelf, a motor driven air pump detachably supported by the shelf, and an electric wiring installation having portions thereof permanently mounted on the table 10 and on the air pump, and means for disconnecting said portions simultaneously with the removal of the air pump from said table, said means comprising male connector members rigidly secured in upstanding position on 15 the shelf and corresponding engageable female members fastened to the baseboard to extend therein from the bottom side thereof.

5. A surgical apparatus comprising a table having a shelf, a motor driven air pump 20 detachably supported by the shelf, and an electric wiring installation having portions thereof permanently mounted on the table and on the air pump, and means for disconnecting said portions simultaneously with 25 the removal of the air pump from said table, said means comprising male connector members rigidly secured in upstanding position on the shelf and corresponding engageable female members fastened to the baseboard to 30 extend therein from the bottom side thereof, and spaced pins for guiding said connector members to aligning position when mounting the air pump on the shelf.

In testimony whereof I affix my signature.
EDWARD J. SOVATKIN.
